ELECTRIC LIGHT

Charles W. Dake, Chicago, Ill.

Application April 23, 1931, Serial No. 532,255

5 Claims. (Cl. 176—31)

This invention relates to an incandescent filament electric lamp, particularly to one which is theft proof.

It has for one object to provide in connection with such a lamp automatic means for rendering the lamp removable after the filament has burned throughout.

Another object of the invention is to provide in a theft proof lamp means whereby the bulb base may be readily screwed into position in a socket and whereby after having been screwed into the socket it cannot be withdrawn until the filament has been destroyed.

Other objects will appear from time to time in the specification and claims.

My invention is illustrated more or less diagrammatically in the accompanying drawing, wherein:

Figure 1 is a longitudinal cross section through the lamp;

Figure 2 is a transverse cross section taken at line 2—2 of Figure 1;

Figure 3 is a sectional view similar to Figure 2, showing the parts after the lamp is in condition for removal.

Like parts are designated by like characters throughout the specification and drawing.

A is a glass bulb, which may have an integral inwardly extending portion A¹ carrying a stem A². Filament supporting members B B are positioned on the stem A². A filament B¹ is carried by the members B and is fastened at one end to a lead member B² and at the other end to a lead member B³. These members pass through the wall of the extension A¹ and extend upwardly beyond the member A¹, the lead B³ terminating in a plug which forms a part of the lamp assembly, and the lead B² terminating in a laterally bent portion B⁴ which is in electrical connection with the members which will be described herein-after.

Fastened to the glass bulb or envelope A by any suitable means, such as cement C, or the like, is a shell C¹ which may be outwardly flared at one end as at C² where it contacts the glass A. The shell C¹ is provided adjacent its lower edge with one or more outwardly bent lugs or portions C³. Within the shell C¹ is an insulating shell or sleeve C⁴. The shell C¹ and the insulating sleeve are perforated as at C⁵ to permit a latch to move and to extend therethrough in a manner which will be described below. At its upper end the shell C¹ is closed by plug C⁶, formed of insulating material. This plug has its upper, outer edge inclined as at C⁷ and is pro-

vided with a depression C⁸ in its upper face. It may have one or more depressions or cavities C⁹ formed in its lower face. A preferably central perforation C¹⁰ is formed in the plug. At its upper end the perforation C¹⁰ may be restricted or of reduced diameter, as shown in Figure 1. Along its upper edge the shell C¹ may have one or more inwardly projecting lugs C¹¹ which project into and lie within the cavities C⁹ and prevent relative turning of the plug C⁶ and the shell C¹.

D is an outer shell or base which is preferably threaded on a portion of its surface as shown. At its lower edge it terminates in an inwardly directed flange D¹ which engages the lugs C³ of the shell C¹ to prevent or limit relative longitudinal movement of the inner and outer shells. At its upper end the shell D is provided with an inwardly extending flange D² which is inwardly and upwardly bent along the inclined surface C⁷ of the plug C⁶. The shell D has preferably adjacent its upper edge an inwardly directed relatively weak and breakable tongue D³ which projects into the cavity C⁸ of the plug C⁶ and is held therein preferably by a rivet D⁴. D⁵ is an inwardly directed projection formed in any suitable manner upon the outer shell D.

E is a supporting member positioned in the plug C⁶. E¹ is a second supporting member which may be longer than the member E. E² is a contact member positioned in the upper end of the perforation C¹⁰ of the plug C. A connection E³ leads from the contact member E² to a resistance E⁴ which is supported between the members E and E¹. A second resistance member E⁵ connects the lead B³ with the laterally bent portion B⁴ of the lead B². The member B⁴ is connected to the resistance E⁴ by a connection E⁶. E⁷ is a link fastened at one end to the upper end of the lead B³ and, therefore, in circuit with the resistance E⁵ which is also connected to the upper end of the lead B³. At its other end the link E⁷ is joined to a latch member E⁸ which is positioned opposite and adapted to be moved through the perforation C⁵ under the influence of a spring E⁹. When the lamp is in operation and before the filament has been destroyed, the parts are held as shown in Figure 2 by a non-conductive holding member E¹⁰, and the outer and inner shells are not locked together and may have relative movement. The member E¹⁰ is of a material which will be destroyed or weakened under the influence of heat. When a sufficient current passes through the resistance E⁵ to heat that member above a predetermined point, the

effect of its heat upon the holding member E^{10} is such as to break it or destroy it or to weaken it to such an extent that the spring E^9 breaks it. After the filament has been destroyed so that the latch may move from the position shown in Figure 2 to that of Figure 3, the latch projects through the inner shell and engages the indent member D^5 of the outer shell and thus reverse rotation, that is to say, rotation to screw the bulb out of the socket, becomes effective for that purpose and the inner and outer shells move together when the lamp is rotated in the direction to screw it out of the socket.

The use and operation of my invention are as follows:

The lamp of this invention, to be used, is positioned in a socket and while it may be arranged to be seated in the socket in any fashion, in the particular form shown herewith it is screwed into the socket. After it has been seated in the socket, a certain additional rotation will break the member D^3 , thus destroying the connection between the inner shell C^1 and the outer shell D and permitting relative rotation of the two. Thereafter, rotation of the lamp does not rotate the outer shell D and since it is that shell which engages the socket, the rotation of the lamp is not effective to remove the lamp as a whole from the socket and until some means is found for re-connecting the inner and outer shells, rotation of the lamp itself is without effect on the outer shell D .

When the lamp is in use, the resistance E^4 acts as a capacity resistance, limiting the flow of current into the lamp. The resistance furnished by the filament B^1 and that offered by the resistance E^5 are together equal to the resistance offered by the differential or capacity resistance member E^4 .

When the filament is destroyed or in fact when any part of the filament circuit, which includes the filament and the leads B^2 and B^3 beyond their connections with the resistance E^5 , is destroyed, all of the current passing through the lamp must pass through the resistance E^5 . This resistance being of less capacity than the resistance E^4 is heated when the entire volume of current passing through the light is carried by it. The added heat of the resistance E^5 is effective either to fuse, burn or otherwise destroy the retaining member E^{10} or else so to weaken that member that the strength of the spring E^9 is sufficient to break it. When the retaining member E^{10} is broken the spring then moves the latch from the position shown in Figure 2 to that shown in Figure 3, and the inner and outer shells are then so locked that rotation of the bulb carrying with it the inner shell, will rotate the outer shell and thus the lamp as a whole may be removed. The lead B^3 is sufficiently flexible to permit its being bent or moved slightly out when the latch moves from the inoperative to the operative position.

It will be realized that whereas I have herewith shown and described a practical operative device, nevertheless many changes might be made in the size, shape, number and disposition of parts without departing from the spirit of my invention and I wish, therefore, that my showing be taken as in a sense diagrammatic.

I claim:

1. In combination in an electric lamp, a bulb, a shell secured to said bulb, a second shell positioned about said first shell, a breakable member joining

them, the shells adapted to have relative rotational movement when the breakable member is broken, a latch movably mounted and adapted in one position to lock the shells against relative rotation, means destructible by heat, normally holding the latch in inoperative position, a filament within said bulb, a resistance element of greater resistance than that of the filament, and a second resistance element of less resistance whereby when the filament is intact current will flow through the latter, and whereby when the filament is broken, the current will flow through the last mentioned resistance to heat the same and thereby to destroy the destructible element.

2. In an incandescent filament electric lamp having a lamp globe with a lighting filament therein and an inner base shell attached thereto, and leads for conducting electricity to and from said filament and extending into the said base shell; a heat destructible member and an electrical resistance element associated therewith and connected to the opposite leads; a second base shell surrounding the first said base shell and a latch engaging the base shells upon the parting of the heat destructible member.

3. In an incandescent filament electric lamp having a lamp globe with a lighting filament within the globe, leads connected to the lighting filament and extending therefrom; a base shell secured to the said lamp globe and electrically connected to one of the leads by a spring pressed latching mechanism held in unlatched position by a heat destructible member associated with an electrical heating resistance connecting the said leads, whereby electricity flowing in the heating resistance will heat the same and part the heat destructible member and free the latch to engage the base shell attached to the lamp globe to a base shell about the said globe shell.

4. In an incandescent filament electric lamp having a lamp globe with a lighting filament and leads for conducting electricity therein and a base shell secured thereto, a second base shell surrounding the first named base shell and separable therefrom by force exerted to screw the second base shell into a lamp socket and connected together by a spring pressed latch normally held in unlatched position by a heat destructible member associated with an electrical heating resistance whereby an excessive flow of electricity in the heated electric resistance will destroy the heat destructible member allowing the latch to move to latched position of the first and second base shells for unscrewing from the lamp socket.

5. In an incandescent filament electric lamp having a lamp globe, inner and outer base members; a spring pressed latch for making engagement of the base members; a lighting filament within the globe and leads extending from the filament; an electrical resistance connected to each of said leads in spaced relation to the lighting filament; a heat destructible member associated with the said resistance for holding the said latch in unlatched position and allowing the latch to be moved to latched position when destroyed or parted by heat from the said resistance; and an electrical resistance having at least as great a resistance as the combined resistance of the lighting filament and the first mentioned, between the lamp socket member and one of the leads.

CHARLES W. DAKE.
